KNIFE SHARPENING MECHANISM FOR
CUTTING MACHINES

Frederick J. Clark and Frederick G. Clark, Buffalo, N. Y., assignors to Eastman Machine Company, Buffalo, N. Y.

Application January 19, 1940, Serial No. 314,666

8 Claims.

(Cl. 51—246)

This invention relates to improvements in knife-sharpening mechanisms for cutting machines of the type, commonly used for cutting cloth and other sheet materials, having an upright, vertically reciprocating knife with a substantially vertical cutting edge which can be caused to follow a desired pattern or line of cut in a lay of cloth or other material by appropriately moving and guiding the machine about upon the supporting table for the material.

One object of the invention is to improve in certain respects, hereinafter pointed out, sharpening mechanisms of the general character disclosed in U. S. Letters Patent No. 2,183,786, granted December 19, 1939, to Frederick J. Clark (one of the applicants hereof), assignor to Eastman Machine Company.

Further objects of the invention are to provide efficient and desirable drive means of novel construction for the knife grinding means or elements of sharpening mechanisms for such machines; also to provide novel and improved means for guiding and holding the flexible band grinding means or belts of such mechanisms in sharpening contact with the machine knife.

These and other objects and advantages of the invention will appear more fully from the following specification of the preferred embodiment of the invention, disclosed in the accompanying drawings, and the novel features of the invention will be set forth in the appended claims.

In the accompanying drawings:

Fig. 1 is a front sectional elevation on line 1—1, Fig. 2, of a cutting machine equipped with knife-sharpening mechanism embodying the invention.

Fig. 2 is a side elevation thereof, partly in section, on line 2—2, Fig. 1.

Fig. 3 is a fragmentary front elevation of the means for holding the sharpening belt away from the knife when it is moved below the lower end of the knife.

Fig. 4 is a sectional plan view of the grinding means.

Fig. 5 is a sectional elevation thereof and of the grinder carriage on line 5—5, Fig. 4.

Fig. 6 is a section on line 6—6 of Fig. 4.

Fig. 7 is an enlarged, more or less diagrammatic, sectional plan showing the relation of the grinding belts and holding elements to the knife.

Fig. 8 is a sectional plan view of holding and guiding means of modified form for the sharpening belts.

Fig. 9 is a side elevation thereof.

Fig. 10 is a sectional view thereof on line 10—10, Fig. 8.

Fig. 11 is a sectional plan thereof on line 11—11, Fig. 10.

The cutting machine, aside from the knife-sharpening mechanism and associated parts, may be of the construction illustrated in the drawings or of other known or suitable construction. As herein disclosed, it comprises, as usual, a base 15 adapted to rest and be moved about upon the table or support-surface on which material to be cut lies; an upright, rigid standard 16 rising from the base and supporting a stationary frame or housing 17 of an electric motor 18, which reciprocates the vertical knife 19 in a guide slot in the front of the standard through drive connections comprising a slide to which the knife is attached at its upper end and which is connected by a pitman 21 to a crank wheel 22 on the front end of a horizontal rotary shaft of the motor. 23 indicates the usual presser foot fixed to the lower end of a rod 24 which extends vertically in front of the knife 19, forming a guard therefor. This rod is adjustable vertically in a suitable guide 25 on the frame and is releasably fastened by means (not shown), to support the presser foot at different elevations suited to different lays of material to be cut. The rear end of the presser foot shown is bifurcated and straddles the front edge portion of the standard to assist in preventing lateral deflection of the guard rod.

In the preferred embodiment of my invention illustrated in the drawings, the knife is sharpened by flexible band grinding means, preferably comprising flexible belts or strips 30 and 31, having grinding surfaces of carborundum or other suitable abrasive material, disposed and operated in such a way that they travel in sharpening contact with opposite sides of the edge portion of the knife. Said grinding means, like those shown in the aforesaid patent, are power driven, for example by the knife-operating motor 18, so that the band stretches or portions of the belts which contact with the knife travel at high speed past the latter, and they are mounted on a grinder carriage 32 arranged to be moved up and down along the knife to enable the sharpening of the knife edge throughout its full length. Said band grinding means, together with the drive mechanism therefor, and other operative parts of the sharpening mechanism may be mounted, as disclosed in said patent, on a cover-piece or housing 33, which is stationarily but removably secured in place at the front of the machine and serves to cover the crank wheel 22 and other parts of the knife-operating mechanism.

The mechanism for driving the knife-grinding means is preferably constructed as follows:

35 and 36 represent two vertical shafts arranged in front of the knife at opposite sides of the plane thereof, to rotate and slide axially in suitable bearings 37 and 37a in the housing 33. These shafts extend downwardly out of the lower end of the housing with their lower portions journaled and held from axial movement in suitable bearings in the grinder carriage 32 so that the shafts will move up and down with the carriage. The shafts may extend through and above the upper end of the housing, thereby enabling the shafts to be made long enough to permit sufficient vertical travel of the grinder carriage for sharpening a knife of the maximum length without requiring the housing 33 or the machine to be of objectionable height. Shafts 35 and 36 are rotated in opposite directions by gearing comprising a train of intermeshing pinions 39, 40 and 41 which are held from endwise movement in a chamber 42 in the lower portion of the housing 33, and shafts 35 and 36 are connected to rotate with pinions 39 and 40 but slide axially therethrough, as by keys projecting from the pinions into longitudinal keyways 43 in the shafts.

The toothed pinions 39-41 are shown disposed with their axes parallel, and the pinion 41 is splined on the lower end of a third shaft 44. Preferably, this shaft is journaled in suitable bearings in the housing 33 at one side of shafts 35 and 36 and is geared at its upper end, as by two intermeshing spiral toothed pinions 45, 46 to a horizontal shaft 47 on which is fixed a wheel 48 arranged to be driven by the crank wheel 22. As shown, the shaft 47 and pinions 45, 46 are suitably mounted in a gear casing 49 which is arranged above the housing 33 to move vertically toward and from the same, as on guide posts 50, one of which is shown in Fig. 2, fixed to and rising from the housing 33 through guide holes in the gear casing. The gear casing is pressed downwardly to hold the wheel 48 in driving engagement with crank wheel 22, as by springs 51 surrounding posts 50 between the gear casing 49 and nuts or heads at the upper ends of the guide posts. The wheel 48 may be driven by frictional contact with the crank wheel, for which purpose the latter may be provided with a peripheral band or tire 52 of rubber or other material adapted to give the necessary frictional contact between the wheels for properly driving the wheel 48 and the grinding means geared thereto. Pulleys 53 and 54 fixed directly on the lower ends of shafts 35 and 36, constitute supporting and drive pulleys for the knife-sharpening belts 30 and 31. Each of the belts 30 and 31, as in the aforesaid patent, passes around one of the drive pulleys 53, 54 and an idler pulley 55, the idler pulleys being journaled on spring-pressed mountings 56 movable toward and from the drive pulleys on rearwardly projecting legs 57 of the grinder carriage which straddle the knife standard. These movable idler pulleys maintain the belts under suitable tension and allow ready removal and renewal of the belts.

When sharpening the knife, the grinder carriage 32 will be moved down and up from an upper position spaced somewhat below the lower end of the housing 33 to cause the belts 30, 31 to grind all portions of the knife edge, and the springs 51 will hold the wheel 48 in driving engagement with the crank wheel 22, and hold the lower end of shaft 44 projecting below the bottom of housing 33. The drive gearing described

will then rotate the belt pulleys 53, 54 and the drive belts 30, 31 for sharpening the knife. When the sharpening of the knife is completed, the grinder carriage is raised to its highest, inoperative position, and in doing this the carriage will engage and lift the shaft 44 and gear casing 49, thus shifting the wheel 48 out of driving engagement with the crank wheel 22 and stopping the motion of the grinding means. When the grinding means are not in use, the grinder carriage is held up in the inoperative position shown in Figs. 1 and 2, by suitable means, such as the latch disclosed in said patent.

By constructing the drive gearing for the grinding means as described, the pulleys for the grinding belts are fixed directly to the sliding shafts 35, 36, gearing on the grinder carriage is eliminated, and only two gear trains comprising five pinions in all, are required. Furthermore, no tubular or telescoping shafts are necessary and the gearing is composed wholly of rigid shafts and gear wheels. The mechanism is also compact, does not obscure the view of the operator in the use of the machine for cutting and does not lessen the desired, attractive, trim appearance of the machine.

In said patent, the two sharpening belts, which are disposed one above the other, or in staggered relation, are yieldingly pressed into grinding contact with opposite sides of the edge portion of the knife by spring pressed fingers. These fingers, as shown in the patent, are pivoted on the carriage legs and have fixed portions which bear against the back faces of the belts, and against which the belts travel, to hold the belts against the knife.

A cutting machine of the type for which the sharpening mechanism is designed is used at different times for cutting cloths or materials which differ greatly in physical characteristics. A very keen edge has to be kept on the knife to efficiently cut some kinds of materials, while some other materials are very hard or tough, and if too thin an edge, or a feather edge is formed on the knife, such materials will quickly damage or dull the edge, thus destroying or greatly impeding its cutting action. But the operators of such machines are not ordinarily the type of skilled mechanics who can be relied upon to sharpen the knife to provide one or another kind of edge as may be best suited to meet the requirements of properly cutting such different kinds of materials, and it is important that the sharpening mechanism be designed so as not to require the skill of a sharpening expert during the use of the machine. Due to the high speeds at which the grinding belts travel, the frictional contact of the belts with the parts of the devices that hold and guide the belts in grinding contact with the knife will wear or cut the surfaces of such parts, so that if such parts are fixed, or incapable of adjustment or renewal, they will become so worn in a comparatively short time as to cause change in the positions of the belts relatively to the knife edge and thus improperly grind the edge or change the character of the edge ground by the belts.

In order to avoid this objection and provide guide and holding devices for the belts having the portions or surfaces which engage the belts constructed so that they can move to repeatedly present new engaging surfaces for the belts and thereby prevent the engaging surfaces from being worn or ground to an objectionable extent;

or so that they can be changed or adjusted to present new surfaces for engagement with the belts before the engaging portions become objectionably worn, or in order to change the relation of the belts to the knife so as to grind different kinds of edges, the guide and holding devices for the belts as herein disclosed are constructed as follows:

As shown in Figs. 1-7, these devices comprise arms 60 suitably pivoted at 61 on the underside of the carriage legs 57 and extending forwardly from their pivots at opposite sides of the knife. Near the edge portion of the knife a guide roller 62 is journaled, as by a screw stud 64, to rotate freely on each pressure arm 60. These rollers 62, which may be metal rollers, are arranged so as to bear against the back faces of the inner runs or stretches of the belts at points adjacent to, and preferably slightly in front of, the edge of the knife, and are yieldingly pressed against the belts, as by springs 65 coiled about the arm pivots 61, with the opposite ends of each spring engaging the related pressure arm and the carriage leg. The springs act to press the rollers and the belts toward the knife. Preferably, the guide rollers are located, as indicated in Fig. 7 of the drawings, so that each belt will be yieldingly pressed against the edge portion of the knife slightly in rear of the point of tangential contact of the belt with the roller 62. By this disposition of the parts, the roller does not form a strictly rigid backing for that portion of the belt which is in grinding contact with the knife, but there is more or less tendency for the belt to leave the periphery of the roller where the belt contacts with the knife. Since the belt is stretched or held under tension between its driving and idler pulleys, and the guide roller deflects the portion of the belt which it engages toward the knife, there is some drag of that portion of the belt which is held in grinding contact with the knife and, as a result, an improved sharpening of the knife is obtained.

Because of the described relationship of the grinding belt, guide rollers and knife, the grinding belts will give the knife the required keen edge having relatively long and substantially flat rather than hollow ground bevel faces, but will be prevented from forming an edge which is too thin to stand up when cutting some kinds of materials with which the machine has to be used. On the other hand, the belts will not grind a short hollow ground edge such as would be produced by the use of circular abrasive wheels. Since the guide rollers are rotated by contact with the belts, they will wear very much longer than fixed or stationary guide surfaces contacting with the belts, and will operate a long time without being worn to an extent sufficient to interfere with the proper sharpening action of the belts.

Figs. 8-11 illustrate belt guide and holding devices of a modified construction in which, instead of the freely rotating rollers 62, guide blocks 70 are mounted on the pressure arms 60 in such a manner that the blocks can be adjusted to present different portions thereof to engage the belts so that before one portion becomes worn to an objectionable extent, the position of the block can be readily adjusted to present a new engaging surface to the belt. As shown in these figures, each block 70 is rotatably mounted on a pivot stud 71 fixed on the arm 60 and is provided with cross grooves 72 in its upper end, in either of which grooves a pin or lug 73 fixed on the underside of the arm 60 is adapted to engage for pre-

venting or limiting rotation of the block on the pivot. The block, as shown, is removably secured on the pivot stud by a screw 74 which is screwed into the stud and has an enlarged head underlying the lower end of the block. A coil spring 75 surrounding the stud in a central cavity in the block reacts between the screw head and the bottom of the block cavity to press the block upwardly against the arm 60 and thus prevent the disengagement of the lug 73 on the arm from the groove in the upper end of the block. By loosening the screw and pulling the block outwardly sufficiently to disengage the lug 73 from the block groove, the block can be turned to engage the lug in another groove and thus hold the block in a different position to present a different surface portion thereof for bearing against the belt. The grooves in the block are somewhat wider than the lug, so that notwithstanding the projection of the lug 73 into any one of the grooves, a limited angular or rotational adjustment of the block is permitted. This allows the angle between the block face, which engages the belt, and the knife edge to be altered sufficiently to shorten or lengthen the bevel ground by the belt on the knife edge, and thus enables the character of the edge to be changed to best suit the material to be cut. The pressure of the spring 75 will retain the block at the angle to which it is thus adjusted. It will be understood that this angular adjustment is independent of the rotation of the block to different positions to present different peripheral faces of the block for engagement with the belt.

The block is preferably provided with a projecting handle 76 for conveniently adjusting it without danger to the operator of cutting his fingers. This handle preferably consists of a Z-shaped bar provided with an annular end portion 77 which surrounds the pivot stud between the block and the arm 60, and is seated in an annular recess in the upper end of the block, while an adjacent portion of the handlebar is seated in one of the grooves in the inner end of the block. By this arrangement the block can be turned by the handle, but when the block is to be adjusted to a different angular position on the arm, the handle can be disengaged from one groove in the upper end of the block and engaged in another groove so that the handle may occupy the same position relatively to the arm, in the different adjustments of the block, and the handle will not be placed so as to strike or interfere with the grinding belt by the adjustment of the block.

As best shown in Figs. 3 and 4, the pressure arm 60 for the lower sharpening belt has a forwardly projecting extension 80 with an inwardly directed end portion adapted to engage a cam 81 on the lower portion of the guard rod 24 when the grinder carrier carriage is moved downwardly far enough to carry the lower belt below the lower end of the knife. When this occurs, the cam 81 will move the pressure arm laterally so as to disengage the guide element from the grinding belt. The belt tension will then straighten out the inner stretch of the belt and hold it away from the knife so that the end of the knife cannot strike and cut the belt. The pressure arms are also preferably provided with lugs 82, Fig. 4, adapted to engage the knife guide to limit the inward swing of the arms in case the belts should break, and thereby prevent possible damage by contact of the guide elements with the knife.

We claim:

1. In a knife sharpening mechanism comprising a flexible abrasive band which travels past the knife in a direction toward a point in advance of the knife edge, and means for guiding and yieldingly holding said band in grinding contact with the edge portion of the knife including a guide element which the band travels past and engages only at a peripheral portion thereof adjacent to the extreme edge of the knife, and means for pressing the guide element yieldingly towards the knife, said element being movable toward and from the knife for its yielding action and in addition being adjustable in a direction at an angle to its direction of yielding motion for changing the angular relation of its said band-engaging portion and the band to the plane of the knife.

2. A knife sharpening mechanism comprising a flexible abrasive band which travels past the knife in a direction toward a point in advance of the knife edge, and means for guiding and yieldingly holding said band in grinding contact with the edge portion of the knife including a guide element which said band passes and engages at a peripheral portion thereof adjacent to the edge of the knife, said element having band-engaging surfaces disposed angularly to each other, and said element in addition to its yielding action being rotatably adjustable to present one or another of said surfaces for engagement with the band and also to change the angular relation between the band and the edge portion of the knife.

3. A knife sharpening mechanism comprising a flexible abrasive band which travels past the knife in a direction toward a point in advance of the knife edge, and means for guiding and yieldingly holding said band in grinding contact with the edge portion of the knife including a spring-pressed support, a guide element rotatably mounted on said support and having angularly disposed band-engaging surfaces each adapted for engaging the band at a point adjacent to the cutting edge, a stop on said support, and parts on said element each arranged to cooperate with said stop by rotation of said element to place a different one of said surfaces in band engaging position.

4. A knife sharpening mechanism comprising a flexible abrasive band which travels past the knife in a direction toward a point in advance of the knife edge, and means for guiding and yieldingly holding said band in grinding contact with the edge portion of the knife including a spring-pressed support, a guide element rotatably mounted on said support and having angularly disposed band-engaging surfaces each adapted for engaging the band at a point adjacent to the cutting edge, a stop on said support, grooves in said element disposed at an angle to each other and each of which said stop is adapted to enter by rotary adjustment of said element for placing a different one of said surfaces in band engaging position, said stop having play in said grooves to allow adjustment of said element when any of said surfaces is in operative position to change the angular relation between the band and the edge portion of the knife.

5. A knife sharpening mechanism comprising a flexible abrasive band which travels past the

knife in a direction toward a point in advance of the knife edge, and means for guiding and yieldingly holding said band in grinding contact with the edge portion of the knife, including a spring-pressed support, a guide element rotatably mounted on said support and having angularly disposed band-engaging surfaces each adapted for engaging the band at a point adjacent to the cutting edge, a stop on said support, parts on said element each arranged to cooperate with said stop by rotation of said element to place a different one of said surfaces in band engaging position, and a handle projecting from said element for turning it, said handle being adjustable relatively to the element so as to project in the same direction in different adjustments of the element.

6. In a knife sharpening mechanism for cutting machines having a knife which reciprocates substantially in the lengthwise direction of its cutting edge and has a free extremity, comprising a flexible abrasive band which travels past the knife in a direction toward a point in advance of the knife edge, means for guiding and yieldingly holding said band in grinding contact with the edge portion of the knife including a guide element which said band passes and engages, and a spring for pressing said element against the knife, said sharpening mechanism being movable lengthwise along said cutting edge, a finger projecting from said guide means, and a relatively stationary device arranged in position to be engaged by said finger when said sharpening mechanism is moved toward the free extremity of the knife and constructed to shift said finger when engaged thereby in a direction to remove the band from contact with the knife when the band has been moved past the free extremity of the knife.

7. A knife sharpening mechanism for cutting machines having a knife which reciprocates substantially in the lengthwise direction of its cutting edge, and a guide for the knife, said mechanism comprising a flexible abrasive band which travels past the knife edge, and means for guiding and yieldingly holding said band in grinding contact with the edge portion of the knife including a guide device which said band passes and which engages and presses the band toward the knife, and a part on said device arranged to engage the knife guide to limit movement of said device toward the knife in case of breakage of said band.

8. In a knife sharpening mechanism comprising a flexible abrasive band which travels past the knife in a direction toward a point in advance of the knife edge, and means for guiding and yieldingly holding said band in grinding contact with the edge portion of the knife, including a guide element which said band travels past and engages at a peripheral portion thereof adjacent to the edge of the knife, said element having peripheral band-engaging surfaces disposed angularly to each other, and said element in addition to its yielding action being rotatably adjustable to present one or another of said angularly disposed peripheral surfaces for engagement with the band.
